UNITED STATES PATENT OFFICE.

GEORGE C. MOXON, OF NEW YORK, N. Y.

ENVELOP-CLASP.

1,335,851.

Specification of Letters Patent.

Patented Apr. 6, 1920.

Application filed December 22, 1914, Serial No. 873,485. Renewed April 16, 1919. Serial No. 290,642.

To all whom it may concern:

Be it known that I, GEORGE C. MOXON, a citizen of the United States, residing in the city, county, and State of New York, have invented certain new and useful Improvements in Envelop-Clasps, of which the following is a specification.

My invention relates in general to a fastening clasp and particularly relates to such 10 a device designed for use in connection with clasp envelops and similar stationery.

There is a general objection to metal clasp envelops in that extreme care must be taken in their manufacture to insure registry of 15 coacting parts and even when this accuracy of construction is provided, a contained article of unusual dimensions is very apt to disarrange the registry. Aside from this objection, these envelops require such a 20 multiplicity of operations in fastening the parts together that they have fallen into disfavor especially in mailing establishments where large numbers of envelops are fastened for mailing, and furthermore such 25 devices present free metal prongs, which tend either to become open in transit and lose contents or to catch and damage other pieces of matter assembled therewith.

One of the objects of my invention is to 30 eliminate the above suggested difficulties in devices of this character and to provide a simple, readily and cheaply constructed clasp which will be self-contained and which will quickly and securely retain the fastened 35 parts in position without danger of damaging other mail matter.

Among the other objects of the invention which may be mentioned are to provide a one piece clasp which can be conveniently 40 locked without injury to the fingers of the operator, to provide a clasp which will lie close to the outer surface of the envelop without presenting any exposed ends, which might catch and damage other matter, and 45 to provide such a device which can be easily and cheaply constructed.

Various other objects and advantages of the invention will be in part obvious from an inspection of the accompanying drawings 50 and in part will be more fully set forth in the following particular description of one form of mechanism embodying the invention, and the invention further consists in certain new and novel features of construc-

tion and combination of parts hereinafter 55 set forth and claimed.

Referring to the accompanying drawings:

Figure 1 is a perspective view showing an open envelop with a preferred embodiment of my invention in position thereon; 60

Fig. 2 is a transverse sectional view showing the clasp of Fig. 1 in fastening position.

While the invention is obviously of general application wherever a plurality of penetrable members are to be fastened, it will be described in its application to envelops used in mailing catalogues and the like. In the drawing there is illustrated an envelop having a back portion 1 and a flap 2 designed to overlap the outer portion of said back and close the opening 3 of the envelop as is usual with devices of this character. The clasp 4 is preferably a one-piece sheet metal member having a base portion 65 5 suitably fastened to the back 2, one end portion of which is a strip having parallel 70 edges and bent back upon itself intermediate its length to form a bill portion 6 positioned above and extending parallel to the 75 base portion. The fastening means for the base portion is preferably two or more 80 prongs 7, which may be pressed from the base strip, or where a wide spreading lateral gripping effect on the envelop is desired, the prongs may be in the form of laterally extending arms 7^a integral with and 85 extending laterally from opposite edges of the base portion, which prongs are passed through the back and are clenched in any 90 suitable manner usual in fastening such members to paper articles.

The end of the base portion opposite the bend 8 connecting the base portion with the bill is enlarged to provide a head 9, with its 95 central portion pressed from the general plane of the base portion to provide a hollow recess beneath the head. The head is provided with a slit 10 extending transversely of the length of the bill and parallel to the bend 8. This slit is preferably made by cutting a U-slit therein and pressing the free end of the tongue 11 so formed into the recess presenting an incline parallel to the base and bill with the end thereof opposite the bend attached integrally to the head. 100 105

The free end of the bill is bent inwardly

at a sharp angle toward the base portion to form a finger 12. This finger forms an acute angle with the bill and is positioned relative to the bend so that it will engage the 5 incline intermediate its length when the bill is pressed toward the base portion in closing the envelop.

The finger may terminate in an edge 13 designed to punch its way through the flap 10 2 and may be either straight or may be reduced to form one or more points.

A backing 14 may be positioned across the bottom of the recess to prevent the finger from punching the envelop and injure its 15 contents and to further assist in turning the finger into its locking position hooked under the head. This backing preferably is in the form of an integral extension from the edge of the head opposite the reduced portion of 20 the base which extension is bent back under the head.

It is obvious that the envelop flap or the backing, or both, may be suitably reinforced at the part engaging the clamp by any suitable means as by affixing an extra layer of 25 paper to these members at this place which thus permits the use of light weight paper with this device.

In operation the flap of the envelop is 30 lapped over the open end and positioned between the bill and base portion of the clamp. It is not necessary that the flap be perforated but the flap may be provided with a perforation or a series of perforations to contain 35 the finger, if desired. Pressure is exerted on the bill to force the same into position parallel and relatively close to the base portion or into engagement with the back of the flap. This action forces the finger through 40 whatever portion of the flap happens to be in line with the same and onto the incline at a slight angle thereto. Continuing the pressure at the free end of the bill causes the finger to be bent by the incline until it fits 45 within the slot and hooks under the portion of the head outlining the side of the slot adjacent the bend in which position it is held by the rigidity of the metal.

If the finger is not bent entirely away 50 from the back of the envelop by this operation, the protecting backing tends to further bend the finger into a flat hook with the base portion disposed between the finger and bill.

Should it be desired to unfasten the clasp 55 as when the content is inspected by the post office the bill may be raised from the base which action will cause the finger to open into its original position and permit 60 the escape thereof from the slit. The bill may be again pressed back into position with the finger again hooking into the base and the clasp has not been damaged by this re-fastening operation.

65 By means of a device of this character the

usual registering openings in the envelop flaps may be omitted as the finger on the bill perforates its own opening in the act of fastening the flap in place, which opening is thus formed in its correct position to form 70 a tight closure irrespective of the dimensions of the contents of the envelop.

When the device is in its fastening position there are no loose ends for catching in other mail matter and as the end of the bent finger is contained within the recess of the base head even this end is not exposed to damage the envelop or the fingers of the operator. The parts are fastened by pressing on a flat metal strip and in unfastening 80 the device it is this flat strip which is raised, thus eliminating any cutting by sharp pointed ends. The clasp is exposed and readily accessible should it be desired to open the envelop and there is no danger of mutilating the same.

While I have shown and described, and have pointed out in the annexed claims, certain novel features of my invention and have described the same in connection with an envelop, it will be understood that the device may be used in connection with mailing cards, boxes and the like and it will be further understood that various omissions, substitutions and changes in the form and 95 details of the device illustrated and in its operation may be made by those skilled in the art without departing from the spirit of the invention.

Having thus described my invention, I 100 claim:

1. A one-piece clasp comprising a base portion provided with a flat head provided with an opening and a strip portion extending from said head and bent back upon 105 itself to form a bill, the free end of said bill being provided with an inturned finger adapted to engage in said opening to fasten the bill in position relative to the base and adapted to perforate a penetrable member 110 disposed between the base portion and bill and means for fastening said base portion in position.

2. A one-piece clasp comprising a base portion provided with an opening and an 115 incline leading to said opening, a bill formed integral with said base portion, said bill including a bendable finger projecting toward said base provided with a sharp end and adapted when pressed toward the base 120 to engage said incline and be bent thereby into fastening engagement in the opening.

3. A one-piece clasp comprising a base portion provided with an opening and an incline leading to said opening, a bill formed 125 integral with said base portion, said bill including a straight bendable finger projecting toward said base and adapted when pressed toward the base to engage said incline and be bent thereby into fastening en- 130

gagement in the opening and a backing for said base portion disposed beneath said opening and adapted to intercept the movement of said finger after it has passed 5 through said opening.

4. A clasp comprising a base member adapted to lie on top of a paper member, and provided with means for bending a co-acting member, a coacting member adapted 10 to overlap a second paper member disposed between the base member and coacting member, said coacting member being provided with bendable means on top of the paper member adapted to engage the said first 15 named means and be bent thereby into fastening engagement with the base member, said bendable means being provided with a pointed end adapted to penetrate the second paper member.

20 5. An article of manufacture comprising a stamped sheet metal clasp comprising a base including a head having a raised portion provided with a slit and an incline leading to said slit, fastening prongs projecting 25 from the edge of said base, a bill extending from said base, a finger extending from the free end of said bill and adapted to engage said incline and to be forced thereby into fastening engagement in the slit.

30 6. A clamp comprising two members fastened together at one end by means of a flat bend and adapted to contain a penetrable fabric member therebetween, means for fastening one of said members in position 35 and means, including a piercing finger on one of the members coacting with the other member, for automatically hooking one of said members through the penetrable fabric member and into set position in said fastened 40 member.

7. A clasp for fastening the flap to the body of an envelop comprising a one-piece metal member having a base portion, means integral with said base portion for 45 fastening the same to the body of the envelop, said back portion including part of a strip bent back upon itself to form a bill portion positioned above and extending

parallel to the base portion of said strip and with said bill portion lapping the free edge 50 of the envelop flap, the free end of said bill portion being defined by a bendable finger projecting toward the base, said base being provided with a slit therein, an incline leading to said slit, said incline adapted to engage the finger when the latter is pressed thereon to bend the same into fastening position in the slit and position the same between the base and the envelop.

8. An article of manufacture, consisting 60 of a flexible strip provided with prongs adjacent one end for fixedly attaching the same to an envelop, said strip adapted for folding manually with a single bend whereby one end portion may be superimposed 65 upon the other and one of said ends being provided with a flexible finger bent back at a sharp angle to the adjacent end portion adapted to engage an envelop flap positioned between the superimposed portion of 70 the bent strip.

9. A clasp for fastening the flap to the body of an envelop comprising a one-piece metal member having a base portion, means associated with said base portion for fastening 75 the same to the envelop, said base portion including part of a strip bent back upon itself to form a bill portion positioned above and extending parallel to the base portion of said strip, the free end of said bill portion 80 being defined by a bendable finger having a sharp pointed end projecting toward the base portion and adapted to penetrate a portion of the envelop disposed between the finger and base portion, said base portion 85 being provided with guiding means adapted to engage the finger when the latter is pressed thereon to bend the same into fastening position.

Signed at New York city, in the county of 90 New York and State of New York this 16th day of December, A. D. 1914.

GEORGE C. MOXON.
